(57) **CLAIM**

The ornamental design for a strap template device, as shown and described.

DESCRIPTION

FIG. 1 is a first perspective view of a strap template device showing our new design;

FIG. 2 is a second perspective view thereof;

FIG. 3 is a top plan view thereof;

FIG. 4 is a bottom plan view thereof;

FIG. 5 is a right-side elevation view thereof;

FIG. 6 is a left-side elevation view thereof;

FIG. 7 is a front elevation view thereof; and,

FIG. 8 is a back elevation thereof, showing the strap template device.

The broken lines depicting letters and lines are for the purpose of illustrating the unclaimed portions of the article and form no part of the claimed design.
